UNITED STATES PATENT OFFICE

1,998,007

LOCOMOTIVE

Adolf Giesl-Gieslingen, New York, N. Y.

Application April 4, 1933, Serial No. 664,307

8 Claims. (Cl. 230—96)

My invention relates to steam locomotives wherein the draft required for the fire is created by an exhaust steam jet, and more particularly to the so-called exhaust nozzle from which said steam jet is ejected into the smokestack.

The exhaust nozzle serves the purpose of discharging the draft-creating steam in form of a jet of proper size, direction and velocity, and it usually consists of a casting secured to the end 10 of the exhaust pipe in such a way that it is readily removable for renewal and correction. It is general practice to provide passages of relatively large cross-section through which the steam is being conducted to the exhaust nozzle, while 15 said exhaust nozzle converges toward its outlet, terminating in that relatively narrow opening which is commonly required to impart to the steam sufficient velocity for creating proper draft. Thus, established practice places upon the exhaust 20 nozzle also the function of contracting and accelerating the steam flow. The steam passages are often somewhat contracted near the inlet of the exhaust nozzle, but ultimate contraction is always effected in the exhaust nozzle proper. 25 Therefore, considerable static pressure is being built up in the steam current at the junction between the exhaust nozzle and the passages preceding said nozzle, with the result that it is difficult to keep a tight joint at said junction. Any 30 leakage has the well-known detrimental effect upon the vacuum in the smokebox and consequently upon the steaming capacity of the locomotive boiler. The said joint is invisible inside the smokebox, and difficult to inspect on account 35 of the various screens usually surrounding it, and it cannot be tested for tightness except by filling the engine cylinders and exhaust passages with water which is a very inconvenient procedure. On the other hand, the joint cannot be permanently sealed because the exhaust nozzle must be 40 removable for replacement due to wear etc.

It is a primary object of my invention to create exhaust nozzle arrangements which avoid any 45 leakage of steam at the point where said steam enters the exhaust nozzle, even in case there is only a loose joint between the exhaust nozzle and the adjoining steam passage.

Another object of my invention is to avoid 50 leakage of exhaust steam into the smokebox also

at all other joints that may be situated within said smokebox.

To these ends I form the exhaust nozzle and the steam passages in such a way as to create at the various joints a static steam pressure which is equal or lower than the static pressure in the smokebox.

Another object of my invention is to so shape such exhaust nozzles that they securely and symmetrically direct the steam flow.

In the drawing, Fig. 1 is a longitudinal central section of a conventional locomotive smokebox, showing the simplest form of my invention. Fig. 2 is an enlarged section through an exhaust nozzle similar to that shown in Fig. 1, but fitted 15 with a special design of bushing at the outlet.

Fig. 3 is a transverse vertical section through a special form of my exhaust nozzle in preferred combination with a locomotive, and Fig. 4 is a diagrammatical section through the central axis 20 of the exhaust nozzle shown in Fig. 3.

Referring to Fig. 1: The smokebox 1 into which the gases enter in the direction of the arrow A, the stack 2 and the exhaust standpipe 3 correspond to established practice, except that the 25 said standpipe converges more than usual and culminates in the throat 4 of the diameter d, which throat is preferably accurately machined along the inner surface 5. The exhaust nozzle 6, machined to correctly fit at its lower end to 30 the throat 4, diverges upwardly in the form of an inverted cone having its maximum diameter D at the nozzle outlet.

If the draft appliance is correctly designed, the combined static and dynamic pressure of 35 the exhaust steam at the point of discharge from the exhaust nozzle, will not exceed the so-called critical pressure of 12 pounds per square inch; and if further, exhaust passages and exhaust nozzle are so shaped as to create an orderly flow 40 of steam that does not separate from the diverging walls of the nozzle outlet, then in that case, the exhaust steam at the point of discharge will expand to the pressure in the smokebox and its speed and kinetic energy will be governed by the 45 size of the exhaust nozzle opening at said point of discharge, that is by the diameter D in Fig. 1; while the preceding contraction of nozzle and steam passages will have no influence upon the kinetic energy of the discharged exhaust steam, 50

nor upon the back pressure encountered by the locomotive engine. Furthermore, at all points where the passage is narrower than the outlet of the exhaust nozzle, the static pressure in the exhaust steam will be lower than the static pressure in the smokebox: Therefore, no steam will escape through any opening in the steam-conducting walls and, if the joint between the exhaust nozzle 6 and the standpipe 3 is not tight, smokebox gas will enter the exhaust nozzle as indicated by the arrow 7 and will be entrained by the steam and properly ejected through the smokestack without loss to draft efficiency.

In order to secure perfect filling by the exhaust steam of the exhaust nozzle 6, the same must diverge very gently, preferably by less than one unit of diameter in 5.5 units of length; or in other words, the quotient

$$20 \quad \frac{L}{D-d}$$

should be more than 5.5.

If the exhaust nozzle were of constant cross-section throughout, the pressures on the inside and outside of the joint would be the same; this mode of construction is less desirable, however, since it should be easy to change the effective discharge opening of any exhaust nozzle, and the same basic casting should be fit for various locomotives requiring different nozzle openings. Therefore I prefer to provide an exchangeable bushing at the outlet as shown in Fig. 2. Said bushing 9 is in effect a continuation of the exhaust nozzle 8, having a similar upwardly diverging taper and preferably a substantially cylindrical outlet 10 machined to give the desired opening D. Obviously, with the given angularity of the conical inner surface of said bushing 9, a largest opening D_{max} and a smallest opening D_{min} may be provided. For the same reasons as previously given, no steam can leak out through the seat of the bushing 9 on the nozzle 8.

In Fig. 3, the exhaust nozzle 12 rests directly upon the cylinder saddle 11 without any standpipe such as 3 in Fig. 1 being interposed. From the cylinders 19 of which only one is illustrated, the exhaust steam passes through the steam chest 18 and from there into the exhaust passages 13. Said exhaust passages 13 unite at 14 in the usual manner, and terminate in a converging passage the upper end 15 of which is adapted to receive the exhaust nozzle 12. According to my invention, the diameter d' of the said passage 15 at the junction with the exhaust nozzle is smaller than the diameter D of the nozzle outlet and therefore the said junction possesses the characteristics described in connection with Fig. 1. In this embodiment of my invention, however, the exhaust nozzle is not wholly divergent but first continues to converge until a minimum diameter (or cross section) d is reached, and then diverges upwardly. This feature is of no effect upon the pressures and velocities in the steam flow at either the joint or the discharge opening, but it serves the purpose of more securely directing the steam jet coaxially with the exhaust nozzle. This is due to the fact that the steam jet seeks to retain the direction imposed upon it in the region of highest speed and therefore I prefer to impart said highest speed within the exhaust nozzle since the same can be accurately machined with more convenience than the exhaust passage. This construction of exhaust nozzle is particularly desirable if instead of the conventional smokestack 16 seated on the smokebox 17, the construc-

tion claimed in my copending application Serial No. 655,161 is used.

In order to force the exhaust steam to follow the nozzle walls, the converging and diverging parts should not be too sharply conical and analogous to the explanations given with Fig. 1,

$$\frac{L}{D-d}$$

and

$$\frac{L'}{d'-d}$$

(Fig. 4) should be more than 5.5.

A standpipe analogous to that in Fig. 1 may be interposed between the cylinder saddle 14 and the exhaust nozzle 12 in Fig. 3 if so desired. If the joints of such standpipe are both made smaller in cross-section than the opening D of the exhaust nozzle, neither of the joints will permit any leakage of exhaust steam into the smokebox.

While the above descriptions, for the sake of simplicity, referred to exhaust nozzles of unobstructed circular cross-section, my principles are naturally independent of the cross-sectional shape which may be rectangular or of any suitable form, and which may also change its geometrical form in the course of the steam flow.

It will be seen from the drawing, and particularly from Fig. 3, that I prefer to form the steam-conducting passages in such a way that the steam flow does not encounter any sudden and abrupt changes in cross-section after the passages 13 leading from the steam chest unite at 14. This is not a new principle but it is not generally recognized and in fact it is sometimes proposed to agitate the steam by means of sudden changes in cross-section and/or cross-sectional area, in the belief that the entraining effect of the steam upon the smokebox gas might be increased thereby. My invention does not exclude the use of such means at or near the point of discharge where such agitation might be effective, but I have found it to be essential that no sudden changes in cross-section occur at the joints where I seek to prevent leakage according to my invention. If, for example, the neck 15 of the steam passage were of larger diameter than the outlet D of the exhaust nozzle, then, the static steam pressure at the joint might be higher than the pressure in the smokebox and steam might tend to leak out in spite of the fact that the inlet of the exhaust nozzle is of smaller diameter as shown. The same may be the case if the properly contracted neck 15 would exhaust into a passage of considerably larger inlet area such as illustrated in Fig. 1 of U. S. Patent No. 664,298. Therefore, at the junction of two steam-conducting parts, I prefer to make both the adjoining cross-sectional areas of said parts smaller than the cross-sectional area of the exhaust nozzle outlet, and I further prefer to give said adjoining parts identical cross-sections at their junction.

If two or more exhaust nozzles are being used in a single smokebox, the said nozzles should have the same characteristics as the single nozzles hereinbefore described. In order to prevent leakage of steam in the spirit of my invention, I make the cross-sectional area of any steam passage at the junction of two adjoining parts smaller than the aggregate area of all exhaust openings receiving their steam supply from said junction.

The high steam velocities occurring in all cross-sections which are smaller than the exhaust noz-

zle outlet, naturally are accompanied by high frictional resistance unless the path is straight and the walls smooth. Therefore I confine such small cross-sections to such parts of the exhaust steam line where they serve a distinct purpose as described.

Having thus described my invention and some preferred examples of practical embodiments, I claim:

10 1. In a locomotive using exhaust steam for creating draft, an exhaust nozzle having at its outlet a larger cross-sectional area than at its inlet and having circumferential walls diverging toward its outlet at a rate of one unit increase 15 in diameter in 5.5 or more units of length.

15 2. In a locomotive using exhaust steam for creating draft, the combination with an exhaust nozzle, of a steam-conducting member discharging steam into said exhaust nozzle, characterized by the fact that both the discharge end of said steam-conducting member and the inlet of the said exhaust nozzle offer to the steam flow a smaller cross-sectional area than the outlet of the said exhaust nozzle.

20 3. The combination claimed in claim 2, characterized thereby that the discharge end of the said steam-conducting member and the inlet of the said exhaust nozzle offer to the steam flow cross-sections of substantially identical shape 25 and size.

30 4. The combination claimed in claim 2, characterized thereby that the said exhaust nozzle has a minimum cross-section or throat between its inlet and outlet.

35 5. In a locomotive using exhaust steam for creating draft, the combination with an exhaust nozzle having at its outlet a larger cross-sectional

area than at its inlet and having a minimum cross-section or throat therebetween, of a steam-conducting member discharging steam into said exhaust nozzle, the discharge end of the said steam-conducting member and the inlet of the said exhaust nozzle offering to the steam flow cross-sections of substantially identical shape and size.

5 6. The combination claimed in claim 5, characterized thereby that both the outwardly and the inwardly diverging parts of the said exhaust nozzle are formed by circumferential walls diverging at a rate of one unit increase in diameter in 10 5.5 or more units of length.

15 7. In a locomotive using exhaust steam for creating draft, the combination with a smokebox and a draft appliance comprising at least one exhaust nozzle outlet, of valve chests and exhaust passages cast integrally with a smokebox-supporting saddle, said exhaust passages uniting 20 into a single exhaust passage before entering the said smokebox and discharging the exhaust steam into an adjoining steam-conducting member, characterized by the fact that both the discharge end of the said single exhaust passage and the 25 inlet of the said adjoining steam-conducting member offer to the steam flow a smaller cross-sectional area than the said exhaust nozzle outlet or outlets.

30 8. The combination claimed in claim 7, characterized thereby that the discharge end of the said single exhaust passage and the inlet of the said adjoining steam-carrying member offer to the steam flow cross-sections of substantially 35 identical shape and size.

ADOLF GIESL-GIESLINGEN.
